UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF TONAWANDA, NEW YORK, A CORPORATION OF DELAWARE.

INDEX OR FILE LEAF.

Application filed January 11, 1924. Serial No. 685,574.

My invention relates to indexes or files, and more particularly to a device of this character in which a leaf or carrier is employed to carry or support a plurality of cards containing reference data. In the particular embodiment shown, a plurality of individually moving supporting members or carriers are used to support cards and are of the general type shown in the patent 5 to Robert D. Hayes, No. 1,223,168, dated April 17, 1917. The present invention, in some aspects, may be considered as an improvement upon the structure shown in that patent.

One of the principal difficulties encountered when attempting to improve upon devices of this character, is that in order to increase the range of usefulness of such a device, more parts are usually required, the addition of which tends to increase the cost of manufacture, the labor necessary to assemble the parts, and the weight of the entire device. It has been found that when card-carriers or leaves of the character under consideration are in use, the constant manipulation of the same in order to gain access to the cards for reference, causes the outer edges of the cards to become worn or soiled and the corners of the same become bent, which either interferes with the usefulness of the device or presents an untidy appearance. In some cases, the edges of the cards of one leaf engage the adjacent leaf, or the cards thereon, or inadvertently 25 are caught in or by the clothing of the user and either become disconnected from the carrier or dislocated upon the carrier.

One object of my invention, therefore, is to obviate the disadvantages above referred 40 to, and to provide a means to protect the outer edges of the reference cards.

Another object of my invention is to accomplish these results without appreciably increasing the total weight of the device.

Another object of my invention is to provide means that while protecting the outer edges of the cards, will also be of such construction that the outer edges of each carrying member or leaf will not interfere with 45 an adjacent leaf when the leaves are manipulated.

Another object of my invention is the provision of means for stiffening or re-enforcing the edges of the leaves, particularly the front edges thereof.

Still another object of my invention is to generally improve indexes or files of this character so that the same are economical to manufacture by constructing the same of few parts, and are comparatively simple to 60 assemble, durable under usage by the average operator, neat in appearance and efficient in operation.

To these and other ends, my invention consists of the novel features and combination 65 of parts to be hereinafter described and claimed.

In the accompanying drawings:

Fig. 1 is a front elevational view of an index directory or file, comprising a plurality of leaves embodying my improvements;

No. 2 is a top plan view of the same;

Fig. 3 is an enlarged side elevational view of one of the leaves;

Fig. 3^A is a section on line 3^A—3^A of Fig. 5;

Fig. 4 is a view showing index cards in various stages of being removed from the leaf;

Fig. 5 is a section on line 5—5 of Fig. 3;

Fig. 6 is a section on line 6—6 of Fig. 3;

Fig. 6^A is a section on line 6^A—6^A of Fig. 3;

Fig. 6^B is a section on line 6^B—6^B of Fig. 4;

Fig. 7 is a section on line 7—7 of Fig. 4;

Fig. 8 is a section on line 8—8 of Fig. 4;

Fig. 9 is a section on line 9—9 of Fig. 3;

Fig. 10 is a section on line 10—10 of Fig. 3;

Fig. 11 is an upper corner of a somewhat modified form of leaf;

Fig. 12 is a vertical section through an index tab used with this device; and

Fig. 13 is a side view of the same.

In order to illustrate the principles of my invention, I have shown at 10 a suitable supporting base which carries a pair of guide members 11 and 12, having guiding grooves or slideways 19 therein. Hung between these members 11 and 12 are a plurality of substantially rectangular leaves 13, each consisting of a frame formed by a wire 14 bent, as shown in Fig. 3, to form three sides of the leaf. A thin aluminum sheet or base plate 17 is connected to the wire 14 at all three sides by wrapping the adjacent edges of the same about the wire, as shown at 18. The ends of the wire 14 are bent back and extended rearwardly beyond the plate 17 at 15 and provided with ball-shaped 105

members 16, which ride in the grooves or slideways 19 in the guiding members 11 and 12. The record cards 20, shown in the drawings, are of the type described in the patent to Irving Fisher, No. 1,048,058 dated December 24, 1912. These cards are provided with integral tongues 21 by which the same are slidingly secured to card guide members 22 beneath edge portions thereof 23. The card guide members 22 are secured upon the plate 17 by means of rivets or eyelets 24. Preferably, card guide members 22 are provided on both sides of the plate 17.

Near the bottom of the carriers or leaves 13, suitable retaining clips or hooks 25 are secured, to support from beneath a series of cards mounted upon the carrier.

The outer edge of the thin plate or sheet 17, if not provided with reinforcing means 20 would tend to become distorted because of being constructed of soft and easily bent material and likewise by careless handling might have a tendency to unwrap from the upper and lower frame portions, which 25 would allow the same to spread apart causing the device to become inoperative as an efficient leaf or index of this character. In order to obviate this tendency a novel one-piece edge covering is provided, as shown at 26, which stiffens the sheet or base plate 17 along the outer edge and secures the upper and lower frame portions together. The edge covering is also formed in such a manner that the outer edges of the series of cards 30 on both sides of the leaf are covered and means are provided by which a tab member may be applied to the leaf.

The edge covering 26 is preferably constructed from a relatively stiff non-oxidizing metal such as nickel-silver, or the like. The top and bottom ends of the edge covering 26 are shaped into the form of hollow knobs or bosses 27, which are provided with suitable openings in one side thereof as at 28, so that the same may be slipped over the doubled ends 29 (see Fig. 3^A) of the wire 14 at the forward edge of the plate 17. Ears 30 are pressed inwardly from both sides 31 of the knobs 27 and rest against the plate 17, being connected thereto at 32. Between the knobs 27, the edge covering is pressed together to straddle the outer edge of the base plate 17 as shown at 33, being connected thereto as at 34. The portion 33 of the edge covering extends inwardly over the base-plate 17 a sufficient distance to form gripping surfaces for the fingers of an operator as well as contact surfaces for the clamping portion of a tab member 35. From this 50 point the edge covering is bent obliquely upwardly away from the base-plate 17, as shown in 36, whereby the same is gradually raised above the surface a sufficient distance to allow a series of cards to underlie the 55 same, as shown in Fig. 6^A. After being

raised above the surface of the plate 17 the desired amount, the material is extended inwardly over and parallel to said surface a short distance, as shown at 37. This construction substantially forms an edge covering 70 Y-shaped in cross section, as is clearly shown in Figs. 7 and 8. The extremes of the edge covering portions 36 and 37 are not connected to the knobs 27 but are left free therefrom, as shown in 38, so as to provide 75 a passageway for the cards 20 when the same are removed from the leaf in groups, as at 39, see Figs. 4 and 6^B.

The point of jointure between the oblique portion 36 and the edge portion 33 of the 80 edge covering is preferably located a sufficient distance away from the edge portions 23 of the card-guiding members 22 so that individual cards may be removed from the guiding members by disengaging the remote 85 tongue 21^a, sliding the card toward the outer edge of the leaf to free the adjacent tongue 21^b beneath the edge portion 23, as shown in Figs. 4, 7 and 8. The raised parallel portion 37, however, must extend over the leaf 90 and beyond the edges of the cards thereon sufficiently to cover and protect the same, as shown in Figs. 3, 4 and 7.

The edge covering 26 is secured to the base-plate 17 at 34, preferably by means of 95 a series of spaced insets located along the edge and in the ears 31 at 32. These insets are formed by punching the metal of one side of the edge covering into the surface of the base-plate 17, and forcing the metal of 100 the base-plate at this point into the edge covering at the other side of the base-plate. An indentation 50 is thus formed in the edge covering on one side of the leaf and a raised portion 51 is formed in the edge 105 covering on the other side. The construction is clearly shown in Figs. 7 and 8 at 34, and Fig. 10 at 32. An exceptionally strong and rigid connection results, due to the interlocking of the surfaces. Preferably, the 110 insets 34 extending along the edge, alternate, being pressed in from one side and then from the other so that curling or distorting the edge longitudinally is prevented. The rivets or eyelets 52, as shown in Fig. 11, 115 may be used in place of insets to secure the parts together if desired.

The bulged ends or hollow knobs 27 provide the means whereby the adjacent leaves are spaced from each other at the outer edges 120 thereof, as well as to enclose the frame ends 29, so that when the leaves are swung to and fro the adjacent leaves will not interfere with each other, nor the flanged or raised portions of the edge coverings catch 125 the edges of the adjacent leaves. To eliminate the disturbing clicking noises of metal striking metal, when the knobs contact with each other, bumpers 40 made of leather or the like, are provided and located within 130

the hollow knobs with a portion 41 protruding from an opening 42 provided therein.

The tab member 35 is constructed of two parts 43 and 44, which are connected together by soldering or the like. The portion 43 consists of a piece of material bent into a form substantially U-shaped in cross section, and serves as the clamping means by which the complete tab holder is secured upon the edge of the leaf. A transverse groove 45 is provided in each of the sides of the portion 43, which connects with a longitudinally extending opening 46. The groove 45 and opening 46 are properly located so that when the tab is applied to the leaf the raised portion 51 of the inset will guide the tab being placed thereon and lock the same against removal while lying in the opening 46 after a slight endwise movement of the tab. The portion 44 of the tab 35 is constructed to straddle the member 43 and is open at both sides. A flange 47 surrounds the opening on each side of the portion 44 at three sides thereof under which indicating slips 48 may be slipped and retained.

While I have shown and described a preferred embodiment of my invention, it will be understood that the same is not limited thereto in all of its details but is capable of many modifications and variations which will fall within the spirit of the invention and the scope of the appended claims.

35 What I claim is:

1. In an index or file, a substantially rectangular support for cards or the like, comprising a relatively thin plate, one side edge and both end edges thereof being reenforced by a one-piece structure, and means straddling the other side edge and extending the entire length thereof to reenforce the same.

2. In an index or file, a substantially rectangular support for cards or the like, comprising a relatively thin plate, one side edge and both end edges thereof being reenforced by a one-piece structure, and means straddling the other side edge and extending the entire length thereof to reenforce the same, said means adapted to engage the ends of said one-piece structure to connect the same together.

3. In an index or file, a substantially rectangular support for cards or the like, an edge covering straddling an edge of said support and having a raised portion presenting an inwardly extending flange at least on one side of said support, said flange adapted to cover the edges of cards mounted upon said support, said edge covering terminating at each end thereof in knobs whereby spacing members are formed to space one support from another.

4. In an index or file, a plurality of swingable leaves having means thereon for sup-

porting reference members, edge coverings for the outer edges of said leaves, each of said edge coverings presenting an inwardly directed flange to protect the edges of the reference members and being provided at each end thereof with knobs integral therewith to form spacing means between said leaves.

5. An index or file, a swingable leaf having means for carrying reference members thereon, a covering for one edge of said leaf comprising a strip of material bent about the edge thereof extending inwardly along the surface of the same to form a leaf-gripping surface, and rising obliquely away from the surface thereof and then parallel therewith to form a flange to overlie the edges of the reference members carried thereby.

6. In an index or file, a swingable leaf having means for carrying reference members thereon, a covering for one edge of said leaf comprising a strip of material bent about the edge thereof and extending inwardly along both the front and rear surfaces thereof to form a leaf-gripping surface, and rising obliquely away from said surfaces to form flanges to protect the edges of the reference members carried by said leaf.

7. In an index or file, a leaf having means for retaining reference members thereon, a covering for one edge of said leaf comprising a strip of material bent about the edge thereof and extending inwardly along both the front and rear surfaces thereof into a form substantially Y-shaped in cross-section.

8. In an index or file, a swingable leaf having means for carrying reference members thereon, a covering for the edge of said leaf comprising a strip of material bent about the edge thereof, extending inwardly along the surface of the same to form a leaf-gripping surface and rising obliquely away from the surface thereof to form a flange to protect the edges of the reference members carried thereby, the flanged portion of said edge covering terminating short of the upper and lower ends of said leaf, and the remaining portion extending to the ends of said leaf and formed into knobs to provide spacing means between adjacent leaves.

9. In an index or file, a leaf of the character described having an edge covering along one of its edges, comprising a strip of material bent about said edge and overlying the front and rear surfaces thereof, said covering secured to the edge of said leaf by insets spaced at intervals along the surface thereof whereby the material of said leaf and of said covering is interlocked at the point of inset, said insets alternated along the edge surface by being made first from one side of said leaf and then from the other.

10. In a device of the character described,

a leaf provided with means to retain a plurality of reference members in overlapping arrangement thereon, an edge covering for said leaf extending inwardly beyond the edge of said leaf and with its edges adapted to overlie the edges of the reference members, said edge covering being spaced from the leaf sufficiently to receive a plurality of overlapping reference members at the portion of the covering overlying the same, but the space allowance being uniformly decreased in a direction toward the edge of said leaf.

11. In a device of the character described, a leaf provided with means to retain a plurality of reference members in overlapping arrangement thereon, an edge covering for said leaf extending inwardly beyond the edge of said leaf and with its edges adapted to overlie the edges of the reference members, said edge covering being spaced from the leaf sufficiently to receive a plurality of overlapping reference members at the portion of the covering overlying the same, but the space allowance being uniformly decreased in a direction toward the edge of said leaf, whereby only sufficient space is provided for one card at a point adjacent the leaf surface.

12. In an index or file, a leaf provided with means to retain reference members thereon, an edge covering for the outer edge of said leaf adapted to overlie the edges of said reference members, means to connect the edge covering to the edge of said leaf whereby spaced raised portions are presented along said edge, and a tab adapted to hold an index slip detachably secured upon the edge of said leaf by engagement with the raised portion of said connecting means.

13. In an index or file, a leaf for the purpose described having an edge covering secured thereto by insets, said insets causing the material of said edge covering to be raised at intervals along the edge of said leaf, and a tab member detachably connected to the edge of said leaf by engagement with one of said raised portions of said edge covering.

14. In an index or file, a leaf for the purpose described having an edge covering secured thereto by insets, said insets causing the material of said edge covering to be raised at intervals along the edge of said leaf, and a tab member detachably connected to the edge of said leaf, said tab member including a U-shaped portion adapted to straddle said edge covering and to engage any one of said raised portions thereof.

15. In an index or file, a leaf for the purpose described having an edge covering secured thereto by insets, said insets causing the material of said edge covering to be raised at intervals along the edge of said leaf, a tab member detachably connected to

the edge of said leaf, said tab member comprising a U-shaped portion adapted to straddle said edge covering and to engage any one of said raised portions thereof, and an index slip receiving portion, said index slip receiving portion being provided with means to receive and retain an index slip in both sides thereof.

16. An edge covering for a sheet of material in the form of a leaf or the like, comprising a strip of material a portion of which is bent into the form of a Y in cross section, the stem of the Y composed of a double thickness of material and extending beyond the Y-shaped portion at one end thereof and terminating in a hollow knob.

17. An edge covering for a sheet of material in the form of a leaf or the like, comprising a strip of material bent into the form of a Y in cross section intermediate its ends, the stem of the Y composed of a double thickness of material adapted to straddle the leaf and extending beyond the Y-shaped portion at each end thereof and terminating in hollow knobs.

18. In an index or file, a leaf for the purpose described having an edge covering secured thereto by insets, said insets causing the material of said edge covering to be raised at intervals along the edge of said leaf, one or more of said raised portions of material being on one side of the leaf and the remainder on the other.

19. In an index or file, a leaf for the purpose described, having an edge covering secured thereto by insets, said insets causing the material of said edge covering to be alternately raised first on one side and then on the other, at intervals along the edge of said leaf.

20. In an index or file, a support for cards or the like, an edge-covering straddling an edge of said support, said edge-covering terminating at each end thereof in knobs whereby spacing members are formed to space one support from another.

21. In an index or file, a support for cards or the like, an edge-covering straddling an edge of said support, said edge-covering terminating at each end thereof in knobs whereby spacing members are formed to space one support from another, said knobs being provided with cushioning means located to contact with the knobs of an adjacent support.

22. In an index or file, a substantially rectangular support for cards or the like, an edge-covering straddling an edge of said support, said edge-covering terminating at one end thereof in a knob whereby a spacing member is formed to space one support from another.

23. In an index or file, a leaf for the purpose described, having an edge-covering secured thereto by insets, said insets causing the material of said edge-covering to be

raised at intervals along the edge of said leaf, and a tab member adapted to engage said raised portions and be detachably mounted upon the edge of said leaf.

5 24. In an index or file, a leaf for the purpose described, having an edge-covering secured thereto by interlocked portions of each, said portions causing the material of

said edge-covering to be raised at intervals along the edge of said leaf and forming the means whereby a tab member may be detachably retained upon the edge of said leaf at various positions along the same. 10

In witness whereof, I have hereunto set my hand this 29th day of December, 1923.

WILLIAM H. DAY.
